PROCESS FOR TREATING HYDROCARBON OILS

Filed March 5, 1928

UNITED STATES PATENT OFFICE

STERLING H. DIGGS AND JOHN M. MCGEE, OF CASPER, WYOMING, AND THOMAS S. COOKE, OF NEW YORK, N. Y., ASSIGNEES TO STANDARD OIL COMPANY, OF WHITING, INDIANA, A CORPORATION OF INDIANA

PROCESS FOR TREATING HYDROCARBON OILS

Application filed March 5, 1928. Serial No. 259,314.

The present invention relates to improvements in the art of treating sulfur containing oils, and will be fully understood from the following description, illustrated by the accompanying drawing, in which apparatus suitable for carrying the invention into effect is diagrammatically illustrated.

Referring to the drawing, the numeral 5 indicates a still setting in which is mounted 10 the still 6, illustrated as of the shell or horizontal cylindrical type. Still 6 is provided with feed line 7 and draw-off line 8. From the still, a vapor line 9 leads to the lower portion of a bubble tower 10, which is provided with a cooling oil inlet line 11 and draw-off line 12. A vapor line 13 leads from the bubble tower 10 to a condenser 14 from which the condensate passes into the receiver 15. From the receiver 15 the distillate passes, 20 or, preferably, is forced by pump 16, through line 17, which is provided with a valve 18, into an orifice plate mixer 19. The orifice plate mixer 19 is preferably of the single hole (knot-hole mixer) type and is provided with line 20 through which sulfuric acid may be introduced into the mixer.

The distillate and acid from the mixer 19 pass through line 21 into treating tank 22, which is provided with a valved draw-off line 23. Any suitable means for cooling the treated distillate, the temperature of which is raised by the heat of reaction, in treating tank 22 may be employed. In the illustration given, a coiled pipe 24 is shown through 30 which a cooling fluid may be passed to maintain the material under treatment at the desire temperature. Treated oil is withdrawn from tank 22 through the valved line 25 and preferably is forced by pump 26 through line 27 into the still 28. Still 28 is preferably a steam still, suitably lagged and mounted on still setting 29. It is provided with a steam line 30 and a draw-off line 31. Vapor line 32 leads from still 28 to a point near the bottom of bubble tower 33, which is equipped with a cooling oil line 34 and a draw-off line 35. From the bubble tower 33 a vapor line 36 leads to condenser 37 from which condensate passes through line 38 into receiver

39. The receiver 39 is provided with a valved draw-off line 40.

In the operation of the process, any suitable charging stock may be introduced into still 6 through line 7. A crude oil or any other heavy oil may, if desired, be used. We prefer, however, to use as a charging stock a raw distillate, such as, for example, is obtained from a pressure still. By means of the bubble tower 10, the vapors passing from still 6 through the bubble tower 10 are so controlled as to produce in receiver 15 a crude gasoline with an end point preferably not less than 5° F. and not more than 35° F. higher than that desired for the finished product. This first distillation in practice has been found to eliminate, as bottoms, approximately 40% of the pressure still distillate which it is unnecessary to treat and which may be withdrawn from the still 60 through line 8. It is to be understood that instead of distilling a pressure still distillate in still 6 in order to obtain the desired crude gasoline product, this product may be obtained directly from still 6 when pressure 65 still charging stock is cracked therein or when any heavy oil, such as crude oil, is distilled therein.

The crude gasoline from receiver 15 is passed through the orifice plate mixer 19, where it is mixed with the acid introduced into the mixer through line 20. While acid of any suitable strength may be used, it is preferred to use 98% sulfuric acid. The amount used must, of course, depend upon the sulfur content of the crude gasoline and the allowable total sulfur in the finished product. By way of example, for a gasoline containing .400 to .450% of sulfur, 25 lbs. of 98% acid per 50 gallons has been found to give a finished product of 0.09 sulfur. Although the mixing may be carried on by agitation with air, or other means, it is preferred to use an orifice plate mixer. From the mixer 19 the oil and acid pass into the treating tank 22 in which the treating action takes place, resulting in the polymerization or other changes of the sulfur compounds which will, subsequently, be left in the bottoms upon redistillation. Heavy material, such as sludges, when de-

sired, may be withdrawn through draw-off line 23.

During the treating operation it is preferred to keep the temperature of the oil comparatively low, say below 100° F. It has been found that treatment of lower temperatures improves the color and decreases the formation of alkyl sulfuric acids, esters and oxidation products. For this purpose, the oil in tank 22 may be circulated through cooling brine or, as illustrated in the drawing, a cooling fluid may be passed through coils arranged within tank 22.

The treated oil in tank 22 is withdrawn through line 25 and may be forced by pump 26 through line 27 into still 28. While the polymerized or changed sulfur compounds may be removed by alkali treatment, or other known methods from the crude gasoline, we prefer to redistill the crude gasoline with steam at temperatures preferably below 300° F. It has been found that when the crude gasoline was redistilled with fire alone to a temperature of 500° F., a considerable amount of SO₂ was evolved with an accompanying formation of black tarry materials in the bottoms. By redistilling with steam and thus keeping the temperature of the bottoms below 300° F., a distillate of better color has been secured without the evolution of any substantial amount of SO₂. Steam is introduced into the still through pipe 30, the vapors generated passing through line 32 into bubble tower 33 where a portion of the vapors are condensed. The desired lighter fractions pass out of the bubble tower into vapor line 36 and are condensed in condenser 37. A condensate, having the desired end point, is recovered in receiver 39. The treated gasoline may be sweetened, either before or after the redistillation. Bottoms in still 28, containing polymerized or changed sulfur compounds, may be withdrawn through draw-off line 31.

While the process is particularly adapted for treating light distillates such as crude gasoline, it is clearly applicable for the treatment of other oils.

It is to be understood that the specific details of apparatus and method hereinbefore set forth are for the purpose of illustration and are not intended to be regarded as limitations upon the scope of the claims, except as contained in the following claims.

We claim:

1. The method of treating sulfur containing hydrocarbon oils comprising distilling said oils to form a distillate having an end point not less than 5° F. nor more than 35° F. above that of the desired finished product, treating said distillate with sulfuric acid, and redistilling said treated distillate to form a distillate product having the end point desired.

2. The method of treating sulfur contain-

ing hydrocarbon oils comprising distilling said oils to produce a distillate having an end point not less than 5° F. nor more than 35° F. above that of the desired finished product, treating said distillate with sulfuric acid, and redistilling said distillate at temperatures below about 300° F. to form a distillate product having the end point desired.

3. The method of treating sulfur containing hydrocarbon oils comprising distilling said oils to form a distillate having an end point not less than 5° F. nor more than 35° F. above that of the desired finished product, treating said distillate with sulfuric acid, redistilling with steam said treated distillate at temperatures below 300° F. to produce a distillate having the end point desired.

4. The method of treating sulfur containing hydrocarbon oils comprising distilling a sulfur containing oil to produce a distillate having an end point not less than 5° nor more than 35° F. above that of the desired finished product, treating a distillate product of said distillation with sulfuric acid to polymerize the sulfur compounds therein, maintaining the temperature of said distillate while undergoing treatment sufficiently low to prevent the formation of substantial amounts of alkyl sulfuric acids, esters and oxidation products, and subsequently redistilling said distillate to free the major portion of it from said acid and sulfur compounds.

5. The method of treating sulfur containing hydrocarbon oils comprising distilling said oils to produce a distillate having an end point not less than 5° nor more than 35° F. above that of the desired finished product, condensing the generated vapors, treating the condensate with sulfuric acid to polymerize the sulfur compounds therein, while maintaining the temperature of said distillate below about 100° F., and subsequently distilling said condensate to free the major portion of it from said acid and sulfur compounds.

6. The method of treating sulfur containing hydrocarbon oils comprising distilling said oils to produce a distillate having an end point not less than 5° nor more than 35° F. above that of the desired finished product, condensing the generated vapors, treating the condensate with sulfuric acid to polymerize the sulfur compounds therein, thereby raising the temperature of said distillate, cooling said distillate while undergoing treatment to prevent the formation of undesirable compounds therein, and subsequently distilling said condensate to free the major portion of it from said acid and polymerized sulfur compounds.

7. The method of treating sulfur containing hydrocarbon oils comprising distilling said oils to produce a distillate having an end point not less than 5° nor more than 35° F. above that of the desired finished product,

condensing the generated vapors, treating the condensate with 98% sulfuric acid to polymerize the sulfur compounds therein, thereby raising the temperature of said distillate, 5 cooling said distillate while undergoing treatment to prevent the formation of undesirable compounds therein, and subsequently distilling said condensate to free the major portion of it from said acid and polymerized sulfur 10 compounds.

8. The method of treating sulfur containing hydrocarbon oils comprising distilling said oils to produce a distillate having an end point not less than 5° F. nor more than 35° F. 15 above that of the desired finished product, treating said distillate with 98% sulfuric acid, redistilling said treated distillate to form a distillate product having the end point desired.

20 9. The method of treating sulfur containing hydrocarbon oils comprising distilling said oils to produce a distillate having an end point not less than 5° F. nor more than 35° F. above that of the desired finished product, 25 treating said distillate with sulfuric acid, maintaining the temperature of the distillate while undergoing treatment sufficiently low to prevent the formation of undesirable compounds; and redistilling said distillate to 30 form a distillate product having the end point desired.

10. The method of treating sulfur containing hydrocarbon oils comprising distilling said oils to produce a distillate having an end point not less than 5° F. nor more than 35° F. 35 above that of the desired finished product, treating said distillate with sulfuric acid, maintaining the temperature of the distillate while undergoing treatment below about 100° F., and redistilling said distillate to form a distillate product having the end point desired.

11. The method of treating sulfur containing hydrocarbon oils comprising distilling said oils to produce a distillate having an end point not less than 5° F. nor more than 35° F. 45 above that of the desired finished product, treating said distillate to polymerize the sulfur compounds therein, redistilling said treated distillate to form distillate products having the end point desired, and withdrawing said polymerized sulfur compounds.

12. The method of treating sulfur containing hydrocarbon oils comprising distilling said oils, condensing the generated vapors 55 thereof to form a distillate having an end point not less than 5° F. nor more than 35° F. above that of the desired finished product, mixing said distillate with sulfuric acid, 60 maintaining a pool of condensate and acid so admixed, cooling said pool of the distillate and acid, and subsequently redistilling said treated distillate to produce a distillate of the desired end point.

65 13. The method of treating light hydrocar-

bon distillates comprising distilling said oils, condensing the generated vapors thereof to form a distillate having an end point not less than 5° F. nor more than 35° F. above that of the desired finished product, mixing said 70 distillate with sulfuric acid, and redistilling said treated distillate with steam at temperatures below 300° F. and sulfur in the residue from said steam distillation to produce a distillate of the desired end point. 75

14. The method of treating sulfur containing light hydrocarbon distillates comprising distilling said distillates to produce a distillate product having an end point not less than 5° F. nor more than 35° F. above that of the desired finished product, 80 treating said second-mentioned distillate with sulfuric acid, maintaining the temperature of said second-mentioned distillate below 100° F. while undergoing treatment, and redistilling 85 said second-mentioned distillate to form a distillate product of the end point desired.

15. The method of treating sulfur containing hydrocarbon oils comprising distilling said oils to produce a fraction having 90 the end-point of the desired distillate product and also mixed therewith a fraction having an end point not less than 5° F. nor more than 35° F. above the end-point of said first mentioned fraction, treating said mixed 95 distillates with sulfuric acid to polymerize the sulfur compounds therein, distilling said treated distillates to produce a distillate of the desired end-point, and removing polymerized sulfur compounds in said second 100 mentioned fraction as residue from said second distillation.

16. The method of treating sulfur containing hydrocarbon oils comprising distilling said oils to produce a fraction having the 105 end-point of the desired distillate product and also mixed therewith a fraction having an end point not less than 5° F. nor more than 35° F. above the end-point of said first mentioned fraction, treating said mixed fractions with sulfuric acid to polymerize the sulfur compounds therein, maintaining the temperature of the fractions while undergoing treatment sufficiently low to prevent the formation of undesirable compounds, distilling 110 said treated fractions to produce a distillate of the desired end-point, and removing polymerized sulfur compounds in said second mentioned fraction as residue from said second distillation. 115

In testimony whereof, we have hereunto set our hands this 14th day of February, 1928, and 20th day of February, 1928.

JOHN M. McGEE.
THOMAS S. COOKE.

CERTIFICATE OF CORRECTION.

Patent No. 1,858,394.

May 17, 1932.

STERLING H. DIGGS ET AL.

It is hereby certified that error appears in the printed specification of the above numbered patent requiring correction as follows: Page 2, line 6, for the word "of" read at; page 3, lines 96 and 98, claim 15, for "distillates" read fractions; and that the said Letters Patent should be read with these corrections therein that the same may conform to the record of the case in the Patent Office.

Signed and sealed this 12th day of July, A. D. 1932.
